UNITED STATES PATENT OFFICE.

WILLIAM R. CLOUGH, OF ALTON, NEW HAMPSHIRE.

DESIGN FOR A HANDLE FOR CORKSCREWS.

SPECIFICATION forming part of Design No. 30,234, dated February 21, 1899.

Application filed January 25, 1899. Serial No. 703,385. Term of patent 7 years.

To all whom it may concern:

Be it known that I, WILLIAM R. CLOUGH, a citizen of the United States, residing at Alton, in the county of Belknap and State of New Hampshire, have invented and produced a new and original Design for a Handle for Corkscrews and the Like, of which the following is a specification, reference being had to the accompanying drawing, forming a part thereof and illustrating a side elevation of a handle embodying my design.

The leading feature of my design consists of the form and configuration of the handle, as shown in the drawing.

15 In the drawing, A designates the handle, which, as shown, has the enlarged central por-

tion B, from which portion B the handle is correspondingly tapered toward its ends, as at D D. At the ends of the handle are spherical knobs E.

What I claim is—

The design for a handle for corkscrews and the like; substantially as shown and described.

Signed at Alton, in the county of Belknap and State of New Hampshire, this 17th day of January, 1899.

WILLIAM R. CLOUGH.
